ATTORNEY

UNITED STATES PATENT OFFICE.

SAMUEL H. DUNNING, OF PATERSON, NEW JERSEY.

ROTATING MECHANICAL STOKER.

1,118,748.

Specification of Letters Patent. Patented Nov. 24, 1914.

Application filed July 16, 1914. Serial No. 851,243.

To all whom it may concern:

Be it known that I, SAMUEL H. DUNNING, a citizen of the United States, and a resident of Paterson, in the county of Passaic and State of New Jersey, have made and invented certain new and useful Improvements in Rotating Mechanical Stokers, of which the following is a specification.

My invention relates to an improvement in rotating mechanical stokers, such, for instance, as are employed on locomotives, and more particularly to that part or portion thereof which I have termed the spreader, that is, that portion onto or into which the fuel is conveyed and thereby thrown or spread onto the fire-bed, the object being to provide a device of this character which shall be simple and economical to manufacture, easily and readily assembled, and which, by reason of its formation, will evenly feed or spread the fuel over the desired area.

A further object of the invention is to so construct the spreader that any and all danger of its being injured or destroyed by heat will be overcome, and with these and other ends in view consists in certain novel features of construction and combinations of parts as will be hereinafter fully described and pointed out in the claims.

In the accompanying drawings, Figure 1 is a vertical sectional view of my improved spreader, a part or portion of the conveyer being shown as assembled therewith; Fig. 2 is a top plan view of the device; Fig. 3 is a sectional view taken on the line 3—3 of Fig. 1, looking in the direction as indicated by the arrow; and Fig. 4 is a sectional view taken on the line 4—4 of Fig. 2 looking in the direction as indicated by the arrow.

By reference to Fig. 1 it will be seen that my improved spreader is designed to be located at the top or upper end of a screw conveyer, 5 representing the grate through which passes a cylindrical casing 6, in which revolves the conveyer 7 secured to the rotating hollow shaft 8, the fuel, in a pulverized condition, being conveyed through the cylindrical casing 6 until it is fed or deposited into or onto the flange or shelf of the spreader. This spreader has somewhat the form of an inverted hollow truncated cone, the circular wall 9 being hollow to form a water chamber 10, the upper and outer flaring edge 13 having integrally formed therewith the two cross-arms 11, 12,

also hollow, to permit of a circulation of water through the same, the cross-arms 11 and 12 extending above and beyond the upper edge 13 as clearly illustrated in Fig. 3. Into the arms 11, 12, where such cross at right angles, that is, in a line with the vertical axis of the spreader, is secured the upper end of a hollow shaft or pipe 14, the extreme upper end 15 of which is closed, said pipe being provided with openings 16 within the hollow arms 11, 12, this pipe 14 passing through the hollow shaft 8 and rotated by any suitable means (not shown) and through which is fed water, or other cooling agent, from any suitable source of supply, the water passing up through the pipe and out through the openings 16, into and through the hollow arms 11 and 12, and into the chamber 10 formed by the hollow circular wall 9, it being understood that the pipe 14 is rigidly secured to the spreader in order to rotate the same when in service. The lower or contracted end of the spreader extends somewhat below, and encircles, the upper end of the cylindrical casing 6, the inner surface of the wall 9 bearing against a ring 17 rigidly secured to the casing 6, said wall 9 being provided with an inwardly turned flange or shelf 18 resting upon and over the extreme upper edge of said casing 6 and ring 17. Between the inner surface of the wall 9 and said ring 17 is provided a row or series of balls or rollers 19, in order to reduce the friction between the rotating spreader and said ring. The extreme lower end of the hollow wall of the spreader fits in a hollow ring 20 from which lead outlet water pipes 21, the latter being connected with the tank or reservoir (not shown) containing the cooling agent, this construction and arrangement of parts permitting a continuous flow or circulation of water up through the pipe 14, hollow arms 11 and 12, and the hollow wall 9 of the spreader, and out of the same into the ring 20, and back through the outlet pipes 21, thereby overcoming to a great extent the danger of the spreader and its parts being injured or destroyed by the heat in the firebox. To further assist in preventing injury to the spreader by the surrounding heat, I partially inclose the same within a cylindrical wall or casing 22, illustrated in Fig. 1, and formed from cement, fire-clay, asbestos, or other heat-resisting material, this circular wall extending from the grate

5 upwardly to about the upper edge 13 of the spreader.

In order to avoid any dust or dirt finding its way into the ring 20, in which the lower 5 edge of the spreader rotates, I secure to the wall 9 an inclined shelf or hood 23 extending downwardly and outwardly over the ring 20.

In order to assist in the proper spreading 10 of the fuel by the rotating spreader, I form on the latter the curved ribs or flanges 24 also made hollow as illustrated in Fig. 4 of the drawings, these ribs or flanges gradually increasing in height from their lower ends to 15 about the center of their length, then gradually decreasing in height and merging into the upper edge of the spreader, the highest portion of said ribs being somewhat higher than said upper edge of the spreader, but not 20 as high as the upper edges of the cross-arms 11 and 12, this particular formation serving to assist the cross-arms in evenly throwing or spreading the pulverized material or fuel over the fire-bed.

25 The rotating screw conveyer 7 carries the fuel upwardly until the latter is fed onto the upwardly flaring wall 9 of the rotating spreader, which in turn carries it upwardly, and with a tendency to spread it, the fuel 30 being carried in a circular path by the hollow ribs or flanges 24. A portion of the material is thrown by these ribs or flanges outwardly to a short distance beyond the wall 22, other portions of the material being 35 caught by the cross-arms 11 and 12 and thrown to a greater distance, the result being that the material is evenly spread from the wall 22 outwardly to a distance in accordance with the rate of speed at which the 40 spreader is rotated. In other words, a part of the material as it rides up and over the outwardly flaring wall of the spreader, is, by reason of the flanges, deposited at a short distance from the device, while the cross- 45 arms, being somewhat higher, and of a different shape, throw or spread their portions of the fuel to a somewhat greater distance.

From the foregoing it will be seen that my device is exceedingly simple in construction,

the spreader itself being cast hollow and of 50 somewhat bell-form in one piece, and that by reason of the provision of a constant circulation of water through the same, there is but little danger of its being injured or destroyed by the intense heat surrounding the 55 same.

What I claim is:—

1. A device of the character described comprising in part a spreader formed of somewhat bell-shape, and with a hollow wall 60 forming a water chamber, said spreader being provided with arms extending across the upper and larger end thereof and provided with a water chamber communicating with said former chamber, and hollow ribs formed 65 on the inner side of said spreader.

2. A device of the character described comprising in part a spreader formed with a hollow circular wall and with hollow arms extending across the top thereof; a rotating 70 inlet water pipe rigidly secured to said cross-arms for rotating said spreader and supplying water to the interior thereof, and hollow ribs formed on the inner side of said spreader.

3. In a device of the character described, the combination with a cylindrical casing, an endless rotating conveyer contained within said casing, a spreader located at the upper end of said casing, said spreader comprising 80 a hollow casing, the lower end encircling said cylindrical casing, and the upper end being provided with hollow cross arms, a pipe rigidly secured to said cross arms for rotating the same and supplying water to 85 the interior thereof, said spreader being provided with hollow ribs on the inner side thereof, a ring into which the lower end of said spreader rotates, and outlet water pipes leading from said ring, substantially as described.

Signed at New York borough of Manhattan in the county of New York and State of New York this 15th day of July, A. D. 1914.

SAMUEL H. DUNNING.
